UNITED STATES PATENT OFFICE

162,091

STORAGE CHEST FOR SHOES AND SHOE POLISHING MATERIALS

Irving O. Smart, Westbrook, Maine

Application April 16, 1949, Serial No. 2,077

Term of patent 14 years

(Cl. D33—8)

To all whom it may concern:

Be it known that I, Irving O. Smart, a citizen of the United States, residing at Westbrook, in the county of Cumberland and State of Maine, have invented a new, original, and ornamental Design for Storage Chest for Shoes and Shoe Polishing Materials, of which the following is a specification, reference being had to the accompanying drawing, forming part thereof.

I claim:

The ornamental design for a storage chest for shoes and shoe polishing materials, as shown.

IRVING O. SMART.
